UNITED STATES PATENT OFFICE.

PETER D. HORTON AND GEORGE HORTON, OF OAKLAND, CALIFORNIA,
ASSIGNORS TO FREDERICK GETCHELL, OF SAME PLACE.

PEN-WIPER.

SPECIFICATION forming part of Letters Patent No. 368,589, dated August 23, 1887.

Application filed December 24, 1886. Serial No. 222,504. (No model.)

To all whom it may concern:

Be it known that we, PETER D. HORTON and GEORGE HORTON, citizens of the United States, residing at Oakland, in the county of Alameda and State of California, have invented certain new and useful Improvements in Pen-Wipers, of which the following is a specification.

Our invention relates especially to that class of pen-wipers in which a saturated and dry sponge is employed for wiping the pen, and has for its object the production of a pen-wiper wherein the wet sponge is kept constantly moistened without becoming unduly saturated with water.

To attain this end our invention consists in forming a longitudinal water-chamber in one side of the inkstand and a vertically-bored well containing the saturated sponge adjacent thereto. Within the former, near the outer end, is placed a cork or stopper, the well and chamber communicating with each other by a hole or water-passage in such a manner that when the cork or stopper is removed air will enter the longitudinal chamber and cause a sufficient quantity of water to pass through into the well and saturate the sponge, the degree of saturation being governed by the length of time in which the cork or stopper is kept removed. A transverse hole is bored in one end of the inkstand or sponge-holder, with which an outer slot communicates containing a dry sponge.

In the drawings forming a part of this specification, Figure 1 is a perspective view of an inkstand containing our pen-wiping devices. Fig. 2 is a longitudinal section through line α α , Fig. 1.

Let A represent the inkstand or sponge-holder, within the face of one corner of which is bored a vertical hole to form a well, B, and within the opposite end of the inkstand is bored a longitudinal hole, which forms a water-chamber, C, leaving a partition, C^x, between the two. A passage, D, is made in the lower portion of the partition, so that a water communication is had between the well and chamber. A sponge, E, of suitable size, is placed in the opening of the well, as shown in Fig. 2, and water introduced to the chamber C and the hole communicating therewith made air-tight by the stopper or cork F.

When it becomes necessary to saturate the sponge, the cork is withdrawn, which admits

air to the chamber and causes a sufficient quantity of water to pass into the well, which communicates with the lower end of the sponge, and by capillary action the entire sponge is quickly saturated, when the cork is replaced in the chamber, shutting off any further supply of water to the well. Should the cork, however, be removed a sufficient length of time, the water in the chamber would be absorbed or drawn entirely out of it and pass off through the medium of the sponge and unduly saturate it, and hence only a sufficient quantity of water need be admitted to the well to saturate the sponge from time to time, as occasion requires.

For convenience in forming the longitudinal chamber and communicating passage between it and the well, especially when wood is employed for the inkstand or sponge-holder, a plug, G, may be inserted at the outer end of the chamber, as shown.

Transversely with the longitudinal chamber and well is made a bore-hole, H, in the top of which is cut a communicating slot, H^x, in which a dry sponge or wiper is compressed and held therein, by which the pen is wiped dry after it has been passed over the wet sponge.

Having thus described our invention, what we claim, and desire to secure by Letters Patent, is—

1. The herein-described pen-wiper, composed of block A, having an air-tight water-chamber, C, with a stopper, F, a sponge-containing well adjacent thereto, said well and chamber being separated by a partition having a water-passage therein, and the dry-sponge holder consisting of a transversely-bored hole, H, and a vertically-cut slot, H^x, communicating with said hole, substantially as described.

2. In a pen-wiper, the dry-sponge holder, which consists of the transversely-bored hole or opening made in the end of the block containing a pen-wiper or ink-holder and a vertically-cut slot communicating therewith, in the manner and for the purpose specified.

In testimony that we claim the foregoing we have hereunto set our hands and seals.

PETER D. HORTON. [L. S.]
GEORGE HORTON. [L. S.]
